UNITED STATES PATENT OFFICE.

ARTHUR W. EHLERT, OF LEBANON, OREGON.

RAILROAD-SPIKE.

1,102,485.

Specification of Letters Patent.

Patented July 7, 1914.

Application filed February 24, 1914. Serial No. 320,563.

To all whom it may concern:

Be it known that I, ARTHUR W. EHLERT, a citizen of the United States, residing at Lebanon, in the county of Linn and State of Oregon, have invented certain new and useful Improvements in Railroad-Spikes, of which the following is a specification, reference being had to the accompanying drawings.

10 This invention relates to new and useful improvements in railroad spikes and more particularly to that class which are permanently fastened, after having been driven into the tie.

15 The main object of the invention is the provision of a novel form of railroad spike which, when once driven into the tie may be rendered impossible of withdrawal.

20 Another object of the invention is the provision of a railroad spike which is provided with curved securing arms adapted to engage within the body of the tie after the spike has been driven home and also provided with means to project said arms to 25 their effective position after the spike has been driven into the tie.

A further object of the invention is the provision of a railway spike of the above character which will possess advantages in 30 points of efficiency and durability, is inexpensive to manufacture and, at the same time, will be very efficient and useful in operation.

With the above and other objects in view, 35 the invention consists in the novel features of construction, combination and arrangement of parts as will be hereinafter referred to and more particularly pointed out in the specification and claims.

40 In the accompanying drawing forming a part of this application, Figure 1 is a side elevation of a railway spike constructed in accordance with my invention. Fig. 2 is a longitudinal sectional view of the same. 45 Fig. 3 is a top plan view; and Fig. 4 is a detail transverse sectional view of the head portion of the spike.

Referring more particularly to the drawing, 1 indicates the body of my improved 50 railroad spike, the lower end of which tapers into a point indicated by the numeral 2, said body being preferably formed of hardened steel or any other suitable material of this character. In the construction of the body, the upper end thereof, down to a point above the end 2, is hollow,

as indicated at 3, while the lower end thereof is solid throughout. The body 1 is provided upon opposite sides of the same with openings 4 which are formed at the junction between the hollow portion and the solid portion of the body.

Movably mounted within the hollow portion 3 of the body 1, are the arcuate engaging arms 5, the upper ends of which are enlarged, as shown at 6, to limit the outward movement of the arms through the openings 4. The lower ends of the arms 5 are provided with points 7, whereby when the arms are driven downwardly and out through the openings 4, the points 7 will readily engage within the ties. It will be noted from the accompanying drawing, that the upper end of the solid portion of the body is substantially arcuate, as shown at 8 and the side edges thereof incline downwardly, as at 9 so that the lower arcuate ends of the arms 5, when driven downwardly, will be forced out, so that the points thereof will readily engage within the tie.

It will be noted from the accompanying drawing, that the body portion 1 of the spike is provided at its upper end with the usual engaging flange 10 which projects outwardly from one side thereof and is adapted to be engaged with the base flange of the rail when the spike is driven in position. The upper end of the body 1 is provided at the inner edge of the flange 10 with the perforated ears 11, in which are mounted the ends 85 of the transverse rod 12. Pivotally mounted upon the rod 12, is a cover 13 having downwardly projecting flange 14, said cover being adapted to engage over the upper end of the spike 1 and the flanges thereof project downwardly upon the side of the body. The inner edge of the flange 10 is provided with an arcuate recess 15 which is adapted to receive the sleeve 15' formed upon the inner edge of the cover 13, so that said cover may 90 be swung to an open or closed position, as desired. From this, it will be readily apparent that when it is desired to drive the spike into position, the cover 13 is arranged over the upper open end of the spike 1 and the spike driven into position.

After the spike has been driven into place, so that the flange 10 engages over the base flange of the rail, the cover is raised and the headed plug 16 is inserted within the upper end of the spike, the head 17 of the plug limiting the downward movement of the same. The plug

16 is dropped into the upper end of the spike 1, the lower end thereof engaging with the upper ends of the enlarged portions 6 of the arms 5 and as the plug 16 is driven into 5 the spike by force, the lower curved ends of the arms 5 will be forced outwardly into the body of the tie, said arms being forced outwardly until the enlarged ends 6 thereof engage with the side edges of the opening 4.

10 Thus, after the arms 5 have been driven into position, the spike 1 is permanently held in place. After the above operation has been carried out, the plug 16 is removed and the cover 13 again placed in position against 15 the upper end of the spike.

From the above it will be apparent that I have provided a simple and durable railroad spike which, after once driven into place, is rendered impossible of withdrawal.

20 It will be noted that by having the lower curved surfaces of the arms 5 engaging the inclined portions 9 of the lower end of the spike, said arms are forced outwardly and the points thereof forced slightly up, so that 25 any attempt to withdraw the spike will be frustrated.

It will be further apparent that in driving the arms 5 into position, they will draw downwardly upon the body of the spike so 30 as to more securely engage the flange 10 with the base flanges of the rail.

My device, as herein described and illustrated in the accompanying drawing, is extremely simple in construction and can be 35 manufactured and placed on the market at a comparatively small cost.

It will be apparent that only one plug 16 is to be used in driving the spikes in place.

While I have shown and described the 40 preferred form of my invention, it will be obvious that various changes in the details of construction, and in the proportions may be resorted to for successfully carrying my invention into practice, without sacrificing 45 any of the novel features or departing from the scope of the appended claims.

Having thus described this invention, what I claim is:—

1. A device of the class described including a body having a hollow upper portion, a solid tapering lower end formed on said body, an engaging flange formed at the upper end of the body, a hinged cover adapted to close the upper end of the hollow portion, said hollow portion being provided at 55 its lower end with opposed openings and arcuate arms arranged within the hollow portion and movably disposed within said openings, as and for the purpose set forth.

2. A device of the class described including a body having a hollow upper portion, a solid tapering lower end, the upper portion of said solid end being arcuate in form, said body being provided with opposed openings at the upper 65 end of the solid portion, curved arms arranged within the hollow portion and adapted to be movably disposed within said openings, and a hinged cover secured to the upper end of the body and adapted to close 70 the upper end thereof.

3. A device of the class described including a body having its upper portion hollow and provided at the lower end of said hollow portion with opposed openings, a solid 75 tapering lower end on said body, curved arms arranged within the hollow portion and movable through said openings, an engaging flange formed at the upper end of said body, perforated ears formed on the body 80 adjacent said flange, a transverse pin arranged within said ears, a cover having a sleeve mounted upon said pin, and engaging points formed in the lower ends of said arms, as and for the purpose set forth.

In testimony whereof I hereunto affix my signature in the presence of two witnesses.

ARTHUR W. EHLERT.
